US00D611478S

(12) **United States Design Patent**
Richardson et al.

(10) **Patent No.:** US D611,478 S
(45) **Date of Patent:** ** Mar. 9, 2010

(54) **ELECTRONICS DEVICE CASE**

(75) Inventors: **Curtis R. Richardson**, Fort Collins, CO (US); **Alan V. Morine**, Fort Collins, CO (US); **Jamie L. Johnson**, Fort Collins, CO (US); **Matthew M. Glanzer**, Fort Collins, CO (US)

(73) Assignee: **Otter Products, LLC**, Fort Collins, OH (US)

(**) Term: **14 Years**

(21) Appl. No.: **29/324,499**

(22) Filed: **Sep. 12, 2008**

(51) **LOC (9) Cl.** **14-02**

(52) **U.S. Cl.** **D14/447; D3/218**

(58) **Field of Classification Search** **D14/138, D14/240, 250, 251, 253, 341, 346, 432, 434, D14/440, 447; D3/201, 215, 218, 273, 294; 361/679.01, 679.41, 679.56; 455/556.2, 455/575.1, 573; 248/292.13; D13/108**

See application file for complete search history.

Primary Examiner—Freda S Nunn*(74) Attorney, Agent, or Firm*—William W. Cochran; Cochran Freund & Young LLC(57) **CLAIM**

The ornamental design for an electronics device case, as shown and described.

DESCRIPTION

FIG. 1 is an isometric view of an electronics device case showing our new design.

FIG. 2 is a bottom view thereof.

FIG. 3 is a front view thereof.

FIG. 4 is a right side view thereof.

FIG. 5 is a left side view thereof.

FIG. 6 is a back view thereof; and,

FIG. 7 is a top view thereof.

Broken lines shown in the drawings illustrate portions of the electronics device, and form no part of the claimed design.

1 Claim, 5 Drawing Sheets
